GARAGE DOOR CONSTRUCTION

William D. Ferris, Sterling, Ill., assignor to
 Frantz Manufacturing Co., Sterling, Ill., a corporation of Illinois

Application March 21, 1938, Serial No. 197,051

12 Claims. (Cl. 267—1)

This invention relates to garage doors, and doors for other buildings, but more especially to that particular construction in which the door is in one rigid section, and in which supporting means are provided by which the door is held in an overhead open position, and a vertical closed position.

Generally stated, the object of the invention is to provide a novel and improved construction and arrangement for easily and accurately adjusting the springs which are commonly employed for assisting in the opening of a door of this kind, and for cushioning the closing movement thereof, thereby to change or regulate the spring leverage by which the door is raised into its open position, and by which it is cushioned in its downward movement, or to change the tension of the springs, whereby only a minimum of effort is necessary in the opening of the door into its overhead position, as well as in the closing thereof, and whereby it is unnecessary to unhitch or disconnect the springs in the said adjustment or regulation thereof.

More specifically considered, the object of the invention is to provide a novel construction and arrangement of screw mechanism for providing, in effect, a micrometer screw adjustment of the spring leverage exerted by the springs of a door of this character, or of the spring tension, or both, thereby more accurately to insure the desired balancing effect of the door, in the general operation of opening and closing the same, and to make it possible to do this after everything has been assembled and while each spring remains properly hitched or connected at each end thereof.

It is also an object to provide certain novel details and features of construction and combinations tending to increase the general efficiency and desirability of a garage door of this particular character.

To the foregoing and other useful ends, the invention consists in matters hereinafter set forth and claimed and shown in the accompanying drawings, in which—

Fig. 1 is a vertical section of a garage door embodying the principles of the invention, showing adjacent portions of the doorway and other portions of the building, with the door in partially open position.

Fig. 2 is a view similar to Fig. 1, showing the door in closed position.

Fig. 3 is an inside view, on a smaller scale, of one side portion of the door, and of the adjacent portions of the building, this view being in the

nature of a vertical section on line 3—3 in Fig. 2 of the drawings.

Fig. 4 is a plan view of the screw mechanism forming the means for adjusting the tension of the springs.

Fig. 5 is an end elevation of the parts shown in Fig. 4 of the drawings.

Fig. 6 is a vertical section on line 6—6 in Fig. 4 of the drawings.

Fig. 7 is a view similar to Fig. 1, showing a 10 different form of the invention.

Fig. 8 is a similar view, showing a different form of the invention.

Fig. 9 is a fragmentary view, showing another form of the invention.

Fig. 10 is an enlarged horizontal detail fragmentary section on line 10—10 in Fig. 7 of the drawings.

As thus illustrated, the invention comprises a rigid rectangular door section 1, provided at its upper corners with wheels or rollers 2 that travel on the horizontal tracks or rails 3, rigidly fastened to the building at each side of the upper portion of the doorway 4 of the garage or other building. Normally, in its closed position, the said door 1 occupies a vertical position, as shown in Fig. 2 of the drawings. As shown in Fig. 1, the said door is adapted to swing upwardly into an overhead horizontal open position.

To support the door in its said open and closed positions, two lever arms 5 have their lower ends pivoted at 6 on the lower portion of the door, and have their intermediate portions pivoted at 7 on brackets 8 secured at opposite sides of the doorway inside the building. These lever arms are preferably made of channel iron, with the two channels facing each other. Each channel has a longitudinal slot 9 in the vertical wall thereof, for the pivot bolt 10, and the head of this bolt carries a bracket plate 100 which is threaded to engage the screw 11 that extends parallel with said slot. This screw has a swivel anchorage 12 in the bracket plate 13 that is rigidly secured to the end of the lever arm. The outer end of the screw or threaded rod 11 is provided with a portion 14 for engagement with a wrench or other tool, so that the screw may be rotated to, in effect, move the bracket plate 100 longitudinally of the lever arm 5, and thereby change the

position of the pivot bolt 10, to in effect either lengthen or shorten the distance between the pivots 7 and 10 previously mentioned. It will be seen that the two coil springs 15 are disposed at opposite sides of the doorway, inside the

30

40

55

building, and that the lower ends of these springs are adjustably anchored on the stationary bracket plates 16 that are secured to the inside of the door frame, these plates each having a vertical row of holes 17 by which the bolts for the eye 18 can be shifted up or down, the springs having their lower ends suitably secured to these two eyes, as shown in the drawings. The upper ends of the two springs are connected to sleeves 19 that are rotatably held on the outer end portions of the pivot bolts 10, the latter being clamped firmly in place against displacement in the slots 9, by nuts 20, after the proper desired adjustment has been made.

15 Thus, after the door is installed, the two screws or threaded rods 11 can be adjusted, to give the springs 15 the proper or desired tension, for the necessary or desired spring leverage, so that the door will have a delicate balancing effect when it 20 is raised into its overhead open position, and when it is lowered into its vertical or closed position. In this way, practically a micrometer screw adjustment is provided for varying the action of the springs. When the door is in vertical 25 or closed position, as shown in Fig. 2 of the drawings, the springs are preferably just a little over the center, so that their tension is exerted in a manner to hold the door in closed position. However, as soon as the lower end of the door is 30 swung outward even a slight distance, the tension of the springs is then exerted in a manner to develop a leverage in the arms 5, so that the springs assist in raising the door into its overhead or horizontal open position. Then, when 35 the door is closed, practically the same leverage is used to retard and cushion the downward movement of the door, thereby to prevent jolting and slamming of the door in the operation of moving it into its closed position. In this way, 40 with accurate adjusting means provided, the exact spring action necessary for the desired operation of the door, both in the opening and closing thereof, is insured and the desired result is obtained by the use of adjusting means of a 45 comparatively simple and inexpensive nature.

Moreover, with the construction shown and described, the door and all its parts can be fully assembled, and the action of the springs, and the spring leverage thereof, can be changed or regulated without unhitching or disconnecting either 50 end of the spring, as each spring will remain hitched or connected at each end thereof during such adjustment and regulation as is necessary to obtain the desired balancing effect of the door,— 55 for example, after the door is fully assembled, and then by partially opening the door, as shown in Fig. 1 of the drawings, the screws 11 can then be rotated, to change or vary the distance between the pivots 1 and the bolts 10, thereby in effect to 60 change the length of the shorter end of the lever arm. This is done easily and conveniently, as it obviates the necessity of unhitching or disconnecting the springs, and the adjustment or regulation is accomplished while the springs are under 65 tension, and without disturbing the original hitch or connection at the lower end of each spring. Rotating the screws 11, of course, will in effect, and to some extent, change or vary the tension of the springs 15, obviously, but the purpose is 70 more to change the leverage developed by the springs in the lever arms 5, by in effect changing or varying the length of the two arms, thereby to insure the desired balancing effect of the door in the opening and closing movements thereof, in order to make it possible to open the door with

a minimum of exertion or effort, and to close it with practically no jolting or slamming thereof.

Obviously, when the point of attachment of the spring on the lever arm is moved toward the pivot 1, the tension of the spring when the door is in open position is increased, and the tension when the door is in closed position is decreased; and, vice versa, when the point of attachment of the spring is adjusted away from the pivot 1, then the tension of the spring when the door is in open position is reduced, and is increased for the closed position of the door. It is also obvious, therefore, that the adjustment for the lower end of the spring, afforded by the holes 17, is effective to give the spring any proper or desired tension with relation to any adjustment or change in the spring leverage, for doors of different weights and sizes, as it is obvious that it will require more spring tension and more spring leverage to properly balance a relatively heavy door, and less for a relatively light door; and, in each particular situation, the adjustment or regulation of the spring leverage is easily accomplished while the springs remain hitched or connected at each end thereof, and hence the balancing of doors of different sizes or different weights can be accurately accomplished through the medium of a comparatively simple and inexpensive adjusting means.

As shown in Fig. 7 of the drawings, there are two side springs 21, that are adjustably hitched at their lower ends to the apertured vertical bars 22, and which have their upper ends hitched to cords 23 that extend over stationary sheaves 24, and then down to the brackets 25 that are rigidly secured to the inner side of the door 26, which latter is similar to the one previously described. The bracket plates 27 are rigidly secured to the sides of the door frame, and are provided with vertical slots 28, similar to the slots 9 previously described. The sheaves 24 are mounted on bolts 31 like the bolts 10 previously described. Each bracket plate 27 has a vertical adjusting screw 29, similar to the screws 11 previously described, and each screw 29 has a threaded element 30 thereon, to carry the bolt 31, which is movable in the slots 28, the upper end of each plate 27 having a swivel 32 for the adjusting screw, the upper end of which latter can be engaged with a wrench or other tool to rotate the screw. In this way, by adjusting the two screws 29, one at each side of the doorway, the tension of the springs 21 can be regulated or adjusted to insure the desired balancing effect of the door, when the latter is opened and closed, the door having side links 33 that are pivoted on the brackets 25 on the door, and that are also pivoted on the stationary bracket plates 34 on the door frame. In this way, the door has an overhead horizontal open position and a vertical closed position in the doorway, and the springs 21 serve to assist in opening the door and to cushion the downward or closing movement of the door, and the tension of the springs 21 can be changed or varied, without unhitching these springs at either end, to suit the requirements of doors of different sizes and weights.

In Fig. 8, the construction is similar to that shown in Fig. 7, but in this case the cords 23 are omitted, and the springs 35 have their upper ends hitched directly to the bolts that slide in the slots 36 of the bracket plates 37 on the sides of the doorway, the vertical adjusting screws 38 being similar to those previously described. In this way, obviously, the tension of the springs 35 can be changed or regulated to suit the re-

quirements, by rotating the screws 38, without unhitching the springs at either end thereof, the door 39 and the side links 40 being similar to those shown in Fig. 7 of the drawings.

In Fig. 9 of the drawings, the construction is similar to that shown at the bottom of Fig. 7 of the drawings, except that in this case the bracket plate 41, similar to the bracket plate 22, is provided with a vertical plate 42 that has a vertical slot 43 for the bolt 44 that slides up and down in this slot, similar to the bolts 31 previously described. Each bracket plate 41 has a vertical adjusting screw 45, swiveled at its upper end, similar to those previously described. The springs 46 are hitched at their lower ends to the bolts 44, and in this way, by rotating the screws 45, the tension of the springs 46 can be changed or regulated to suit the requirements.

It will be seen, therefore, that a novel screw adjustment mechanism is provided for changing or varying or regulating the tension of a door-lifting spring, or for changing or varying the spring leverage, thereby to vary the spring tension or the leverage in accordance with doors of different sizes and weights, and it is obvious that, in each form of the invention, this leverage or tension adjustment is possible without unhitching any spring at either end thereof, and is possible without disconnecting any of the parts, after the door is fully installed, wherebv the adjustment of the tension or leverage, or both, can be accomplished readily, from time to time, during the actual use and life of the door.

The invention, therefore, contemplates broadly a garage door construction in which there is a screw mechanism for adjusting the tension of the lifting springs, or the spring leverage, in either the vertical closed position of the door, or in the horizontal overhead open position of the door, without the necessity of unhitching either end of either one of the two lifting springs, by means of a rotary screw threaded rod for each spring, with a threaded non-rotary traveler for each threaded rod, and with each rod swiveled at its end to hold it against endwise displacement on its support, which latter may be either a lever arm or a bracket on the building, and this broad idea is the essence of the invention, inasmuch as this form of screw adjustment was not heretofore possible in overhead door construction of this kind.

Obviously, when the nut 20 is tightened, the traveler 100 is tightly clamped in place, as on the member 5, and this prevents rotation of the screw 11, as when the traveler is rigidly held with the member upon which it is mounted, the screw cannot then be rotated, and this is true of each and every form of the invention shown and described. This means, of course, that the pull of the spring is communicated directly from the traveler to the member on which the latter is mounted, instead of through the screw, for when the traveler is thus rigidly clamped and fixed in position, the screw could be removed, and the spring would still be effectively hitched or connected to the lever 5, or to whatever other member the traveler is mounted upon. But as the screw 11 is held against endwise displacement, by the swivel 12, it follows that the screw cannot be rotated when the traveler is rigidly clamped in fixed position on the guide formed by the slot or by any suitable guiding means.

Thus in each form of the invention the balancing of the door is regulated by the movement of the traveler along the guide, and along the

screw, and in each case the pulling means are applied to the clamping bolt that extends through the traveler and the guide, so that the spring tension is communicated directly to the guide, instead of through the adjusting screw.

What I claim as my invention is:

1. In a garage door system of counterbalancing, whereby the door has a vertical closed position and an overhead horizontally disposed open position, the combination and relative arrangement of a member having a guide, a traveler adjustable back and forth on said member, held to straight movement by said guide, an adjusting screw swiveled at one end in a bearing on said member and disposed parallel with said guide and having screw connection with said traveler so that when the screw is rotated the traveler will move along said guide, while the screw is held against axial displacement by its swivel, holding means for holding said traveler fixed in adjusted position and thereby preventing rotation of said screw and having provisions thereon for the connection thereto of pulling means, whereby the pull exerted is regulated by said adjustment of the traveler, and whereby the balancing of the door may be regulated by the changing of the position of said traveler on said screw.

2. A structure as specified in claim 1, said member being a pivoted lever, so that the leverage thereof is changed by said adjustment of the traveler.

3. A structure as specified in claim 1, said member being held stationary.

4. A structure as specified in claim 1, said traveler having a sheave mounted thereon, for said pulling means.

5. A structure as specified in claim 1, said pulling means comprising a coil spring connected at one end to said traveler and at the other end to a stationary object.

6. A structure as specified in claim 1, said pulling means comprising a coil spring connected at one end to said traveler and at its other end to a movable object.

7. A structure as specified in claim 1, said holding means comprising a clamping bolt extending through said guide, with the head of the bolt engaging said traveler, and with the nut thereof engaging said member, so that the latter is clamped tight between said traveler and nut, when the latter is tightened, with said pulling means swiveled on the end portion of the bolt outside of said nut thereof.

8. A structure as specified in claim 1, said holding means comprising a bolt extending through the traveler and guide, with the head of the bolt against the guide, and a nut on said bolt, said guide being clamped between said nut and traveler, and said pulling means being applied to the outer end of said bolt.

9. A structure as specified in claim 1, said member being stationary to hold said bearing in fixed position.

10. A structure as specified in claim 1, said member being movable to move said bearing on the arc of a circle.

11. A structure as specified in claim 1, having leverage means in which the leverage is changed by the adjustment of the traveler.

12. A structure as specified in claim 1, having tension means in said pulling means in which the tension is changed by the adjustment of the traveler.
